CLAIM

The ornamental design for a combined writing board and pen holder, as shown and described.

DESCRIPTION

FIG. 1 is a perspective view of the combined writing board and pen holder showing our new design; FIG. 2 is a top plan view thereof;

FIG. 3 is a cross-sectional view taken along line 3—3 of FIG. 2;

FIG. 4 is a cross-sectional view taken along line 4—4 of FIG. 2; and

FIG. 5 is a bottom plan view thereof.
